US00D860553S

(12) **United States Design Patent** (10) Patent No.: **US D860,553 S**
Ha et al. (45) Date of Patent: **** Sep. 17, 2019**

(54) **WASHING MACHINE**

- (71) Applicant: **LG Electronics Inc.**, Seoul (KR)
- (72) Inventors: **Youngsoo Ha**, Seoul (KR); **Taewoo Yoo**, Seoul (KR); **Eunyoung Chee**, Seoul (KR); **Jeaseok Seong**, Seoul (KR)
- (73) Assignee: **LG ELECTRONICS INC.**, Seoul (KR)
- (**) Term: **15 Years**
- (21) Appl. No.: **29/689,604**
- (22) Filed: **Apr. 30, 2019**

Related U.S. Application Data

- (60) Division of application No. 29/586,311, filed on Dec. 2, 2016, which is a continuation of application No. 35/501,423, filed on Feb. 26, 2016 (U.S. filing date under 35 U.S.C. 384), and having an international filing date of Feb. 26, 2016, now Pat. No. Des. 808,093.

(30) **Foreign Application Priority Data**

- Sep. 10, 2015 (KR) 30-2015-0046161
- (51) **LOC (12) Cl.** **15-05**
- (52) **U.S. Cl.**
USPC **D32/6**
- (58) **Field of Classification Search**

(57) **CLAIM**

The ornamental design for a washing machine, as shown and described.

DESCRIPTION

The FIGURE is a front, right perspective view of the washing machine showing our new design.

The broken lines in the FIGURE illustrating portions of the washing machine form no part of the claimed design.
